C. H. JOHNSON.

GAME BOARD.

APPLICATION FILED JULY 18, 1918.

1,313,600.

Patented Aug. 19, 1919.

UNITED STATES PATENT OFFICE.

CHARLES H. JOHNSON, OF SACRAMENTO, CALIFORNIA.

GAME-BOARD.

1,313,600.

Specification of Letters Patent.

Patented Aug. 19, 1919.

Application filed July 18, 1918. Serial No. 245,569.

To all whom it may concern:

Be it known that I, CHARLES H. JOHNSON, a citizen of the United States of America, residing at Sacramento, in the county of Sacramento and State of California, have invented certain new and useful Improvements in Game-Boards, of which the following is a specification.

This invention relates to game boards, and 10 the objects of the invention are to provide a game board which has a novel form of gripping means affording a continuous hand grip so that the board may be tilted in various directions as desired, and to also provide a board which has a central pivot so as 15 to enable the same to be tilted in different directions about the pivot.

Further, the invention aims to provide novel means for trapping the balls with 20 which the board is used in the playing of games, and to also provide a board which may be easily taken apart and assembled.

Still further and other objects will later appear and be manifested in the course of 25 the following specification.

In the drawings:

Figure 1, is a perspective view of the invention;

Fig. 2, is a central vertical view; and

Fig. 3, is a like view of a modified form of the invention.

In proceeding in accordance with the present invention, a central support or post 1, is employed on the top of which is suitably secured the circular board 2. A circular guard rail 3, is suitably secured to the upper face of the board or top 2, and has its upper edge portion inturned or overhanging to prevent the balls from accidentally leaving the table 35 or top 2. It will be apparent that the rail 3, is disposed inwardly of the periphery of top 2, so as to thereby provide a continuous circular hand grip 4 of the same thickness as that of the remainder of the top enabling 40 the players to grasp the ring-like part 4 at any point throughout its circumference.

As depicted in Figs. 1 and 2, rods 5 with turnbuckles 6, may be used to connect the post 1 to the top 2, and if desired a wood 50 brace 7 may be used to supplement or entirely take the place of the rods 5, as shown in Fig. 2, this brace at its lower end fitting in a notch 8 cut to conformably receive same in the post 1, and at its upper end may be held by an abutment, such as the screw 9 depicted in Fig. 2. The upper end of post 1

removably fits in a socket or collar 10 secured to the under face of the top 2, so that upon removal of the braces, the post may be also removed and the entire structure thus 60 collapsed.

The post 1, is formed with a passage 11 which latter at its lower end is turned outwardly at an angle and extends through the post periphery. A receptacle 12 for trapping the balls is used and is removably suspended at its upper end from a hook 13 borne by the post while its lower portion is secured by hooks and eyelets 14 to the post at points on opposite sides of and below the 70 angular lower end, of the passage 11.

As shown in Fig. 3, the post is omitted and the balls drop directly into a bag 15, the latter being removably secured by means of a rubber band or metal clasp 16, to a collar 17 75 grooved to receive the band or clasp 16.

In playing of the game, which may be by two, three or more players, the post is seated at its lower end on a table, or other preferred support, and each player is provided 80 with an equal number of marbles, for example ten each, the marbles being grouped and the groups being differently colored so as to enable same to be easily distinguished. One player will then grasp the continuous handle and by tilting of the board in various directions with the lower end of the post as a pivot endeavor to roll his opponents' marbles into the passage 11, whereupon same will be trapped in the receptacle. The next 90 player then proceeds in a like manner but endeavors to roll his opponent's or opponents' marbles into the passage, the players being allotted a like period of time in rotation. The player who first succeeds in trapping 95 his opponent's marbles is winner of the game. The game more particularly is designed to be played with the various groups of marbles representing opposing forces or armies, with the aim of capturing the opposing forces or armies, each player being equipped with a set or group of marbles, and the players being positioned to points equidistantly spaced about the circumference of the board so that the continuous hand grip 100 is available to all of the players regardless of whether or not the board may be turned.

Claims:

1. A game board including a plate having a ball-receiving aperture, a support depending from the center of the plate, a receptacle, means to detachably suspend the recep-

tacle from the support, and a means arranged within the support and communicating with the aperture and receptacle for conveying balls to the receptacle.

- 5 2. A game board including a plate having a ball-receiving aperture, a support depending from the center of the plate, a receptacle, means to detachably suspend the receptacle from the support, said support having a passage with one end of the passage communicating with said aperture and with its opposite end turned at an angle and extending

through and flush with a side of the support and into a side of the receptacle, and means to connect the receptacle to the sides 15 of the support at points below said angular end of the tubular member.

In testimony thereof, I affix my signature in the presence of two witnesses.

CHARLES H. JOHNSON.

Witnesses:

E. S. WARNER,
H. DIXON.
